FIG. 3

To all whom it may concern:

Be it known that I, Jean O. Reinecke, a citizen of the United States, residing at Oak Park, in the county of Cook and State of Illinois, have invented a new, original, and ornamental Design for a Tackle Box or Similar Article, of which the following is a specification, reference being had to the accompanying drawing, forming part thereof, in which:

Fig. 1 is a top plan view of the tackle box or similar article, embodying my new design;

Fig. 2 is a front elevational view thereof; and

Fig. 3 is a cross sectional view thereof, taken along the line 3—3 of Fig. 2.

The dominant feature of my design resides in the portions shown in full lines.

The rear and sides of the box, not shown, are conventional.

I claim:

The ornamental design for a tackle box or similar article, substantially as shown and described.
